UNITED STATES PATENT OFFICE.

THOMAS F. BISHOP, OF INDIANAPOLIS, INDIANA.

STOKER.

Application filed August 29, 1921. Serial No. 496,887.

To all whom it may concern:

Be it known that I, THOMAS F. BISHOP, a citizen of the United States, residing at Indianapolis, in the county of Marion and 5 State of Indiana, have invented a new and useful Stoker, of which the following is a specification.

This invention relates to a stoker for use in connection with furnaces having inclined 10 shaking grates, one of the objects being to provide a hand operated stoker the feed hopper of which can be mounted to swing on the door hinges of the furnace so that access can be had to the interior of the furnace through the door opening without necessitating the dismantling of the apparatus.

Another object is to provide stoking mechanism adapted to be operated by the 20 shaker lever or levers of the furnace, the parts being adjustable to control the amount of fuel fed to the furnace during each stroke of the feeding ram.

With the foregoing and other objects in 25 view which will appear as the description proceeds, the invention consists of certain novel details of construction and combinations of parts which will be hereinafter more fully described and pointed out in the 30 claims, it being understood that various changes may be made in the construction and arrangement of the parts without departing from the spirit or sacrificing any 35 of the advantages of the invention as set forth in the claims.

In the accompanying drawings the preferred form of the invention has been shown.

In said drawings—

40 Figure 1 is a front elevation of the stoker.
Figure 2 is a view partly in side elevation and partly in section.

Figure 3 is a plan view of the lever mechanism.

45 Figure 4 is a side elevation of a slightly modified form.

Referring to the figures by characters of reference, 1 designates hinges upon the front plate of a furnace, and mounted to swing 50 on these hinges is a hopper 2 having a bottom 3 inclined downwardly toward the lower edge of the opening 4 in the plate 5. The inclined grate bars have been shown at 6 and include rocker members 7 adapted 65 to be rocked by shaker bars 8 connected thereto in any well known manner and ex-

tending through the plate 5. Brackets 9 are mounted on the plate 5 and fulcrumed on each of them is a shaker lever 10 connected, as at 11, to one of the bars 8.

60 The inclined bottom 3 of the hopper is slotted longitudinally, as shown at 12, to receive an ear 13 extending downwardly from the bottom of a ram 14 mounted to reciprocate upon the bottom of the hopper. This ram has a longitudinal series of apertures in the bottom thereof whereby the ear 13 can be adjustably connected to the ram, the said apertures being shown at 15. The ram extends throughout the width of the 70 hopper and is overhung by an apron 16 inclined downwardly and inwardly from the front wall of the hopper.

75 Pivotedly connected to the ear 13 is a link 17 extending toward a pair of parallel oppositely extending levers 18 and 19. These levers are connected by links 20 so as to form the sides of a parallelogram, three of the links being preferably employed, and the link 17 is connected to one of the levers at the point where the intermediate links 20 are attached to said lever. A forked block 21 is pivotally attached to the outer end of each lever 18 and 19 and has a stud 22 projecting therefrom. These studs engage the upper ends of levers 23 fulcrumed between their ends upon brackets 24, as shown at 25 and the lower ends of said levers are connected by links 26 to the adjacent levers 10 below their points of connection with the 80 bars 8.

85 Anti-friction rollers 27 may be connected to the ram 14 so as to travel on the bottom of the hopper and cause the ram to work freely.

90 The hopper 2 is adapted to be held in active position by a button 28 and when it is thus located fuel can be placed in the hopper and a portion thereof will gravitate to position back of the ram 14. Thus when 100 one of the levers 10 is oscillated, movement will be transmitted therefrom through the levers and links to the ram and said ram will be reciprocated so as to feed fuel to the furnace while the grate is being shaken. By providing the arrangement of connected 105 levers 18 and 19 the proper actuation of the ram is insured whether it is operated by the oscillation of either or both of the levers 10. These levers and their connections provide 110 a parallelogram which compensates for any variation in the distance between the upper

ends of the levers 23 during separate actuation thereof and, at the same time, affords a strong connection between said levers and the ram 14. It is to be understood that the 5 connection between the links 17 and the ear 13 is sufficiently loose to permit the movement of lever 18 as described. It will also be understood that when one of the levers 10 is actuated to move the ram, the other 10 lever 10 is held stationary in any suitable manner, as is well understood in this art. By detaching the ear 13 from the link 17 and turning the button 28, the hopper can be swung on its hinge to expose the opening 15 4 and give access to the interior of the furnace through said opening.

Obviously instead of mounting the up-standing levers upon intermediate pivots, as shown at 25, levers 29, such as shown in 20 Figure 4 can be used. These levers are ful-crumed at their upper ends on brackets 30, their lower ends being connected to levers 10 by links 32 while the studs 22 engage intermediate portions of the levers 29.

25 What is claimed is:—

1. The combination with a furnace having a feed opening, separate grate actuating levers, and a fuel feeding ram, of levers having lapping inner end portions, and links 30 connecting said portions to form a parallelogram for transmitting motion from either grate actuating lever to the ram, and means connecting the grate actuating levers with the levers of the parallelogram, respectively.

35 2. The combination with a furnace having a feed opening and separate grate actuating levers, of a fuel feeding ram, levers

having lapping inner end portions, links connecting said portions to form a parallelogram, a connection between the parallelogram and the ram, and separate connections between the levers of the parallelogram and the respective grate actuating levers for actuating the parallelogram and ram from either grate actuating lever.

3. The combination with a furnace having a feed opening, a fuel feeding ram movably mounted adjacent the opening, levers having lapping inner end portions, and links 40 connecting said portions to form a parallelogram, of a movable connection between the parallelogram and the ram, grate actuating levers, and operating connections between the grate actuating levers and the respective lapping levers.

4. The combination with a furnace having a feed opening, a hopper hingedly mounted, and a fuel feeding ram movably mounted in the hopper, of means for actuating the ram, said means including movably connected levers, a movable connection between the levers and the ram, separate grate actuating levers, upstanding levers connected to and actuated by the grate actuating levers respectively, and connections between said upstanding levers and the movably connected levers.

In testimony that I claim the foregoing as my own, I have hereto affixed my signature in the presence of two witnesses.

THOMAS F. BISHOP.
